UNITED STATES PATENT OFFICE

171,941

ELECTRIC MASSAGER

Alfonso Iannelli, Park Ridge, Ill., assignor to John Oster Manufacturing Company, Racine, Wis.,
a corporation of Wisconsin

Application October 19, 1953, Serial No. 27,222

Term of patent 14 years

(Cl. D83—1)

To all whom it may concern:

Be it known that I, Alfonso Iannelli, a citizen of the United States, residing at Park Ridge, in the county of Cook and State of Illinois, have invented a new, original, and ornamental Design for an Electric Massager, of which the following is a specification, reference being had to the accompanying drawings which form a part thereof.

The dominant features of my design reside in those portions thereof shown in full lines.

I claim:

The ornamental design for an electric massager, as shown and described.
